UNITED STATES PATENT OFFICE.

CHARLES E. DAMMART, OF MINNEAPOLIS, MINNESOTA.

ENVELOPE-MAKING MACHINE.

Application filed October 25, 1926. Serial No. 144,031.

This invention relates to improvements in envelope-making machines, generally, and more particularly to those machines which are capable of making envelopes having a transparent window in the face thereof, and an object of the invention is to provide means for cutting off portions of transparent window material and applying such severed portions or patches directly onto the envelope blank over the window opening therein, the surfaces of the blank encircling the opening having been previously gummed to secure the patches of window material thereto.

15 A further object of the invention is to provide an envelope-making machine including a hollow cylinder having means therein for supporting a roll of transparent sheet window material, and also having means therein 20 for feeding the window material from the interior of the cylinder through an opening in the periphery thereof, as the cylinder is rotated, and subsequently severing the material at the periphery of the cylinder after 25 the gummed envelope blank engages the cylinder, thereby transferring the severed portion or patch of window material from the hollow cylinder directly onto the envelope blank.

30 A further object of the invention is to provide a mechanism adapted for use in connection with an ordinary envelope-making machine of the type capable of making envelope blanks having window openings in 35 the faces thereof, to cause such a machine to apply a patch of transparent window material over the window opening in each envelope blank, as the blanks pass through the machine, said mechanism having means for 40 varying the size of the patch to suit various sizes of window openings.

A further object is to provide a mechanism for applying transparent patches of sheet material over window openings in the 45 faces of envelope blanks, such mechanism including a hollow cylinder having means therein for supporting a roll of transparent sheet material; a variable speed feeding mechanism in the cylinder for feeding the material therefrom through an elongated opening in the peripheral wall of the cylinder; and a cutting device also in the cylinder for transversely severing the material 50 when a predetermined length has been fed

from the cylinder, the length of the patch 55 thus severed from the roll being governed by the width of the window opening in the blank on which it is to be applied.

Other objects of the invention are: to provide such a mechanism of simple and inexpensive construction, and, which can be applied to various types of ordinary envelope-making machines now in use; to provide a cylinder for supporting the roll of transparent window material, and wherein substantially all of the operating mechanism for feeding and cutting the window material is housed; to provide means for applying the patch of window material directly onto the blank immediately after it is severed from the roll, thus preventing the patch from shifting or moving with respect to the blank when applied thereto; and to provide a mechanism for applying such transparent patches to envelope blanks having means for 75 varying the size of the patch to suit practically all standard sizes of envelope window openings.

Other objects of the invention will appear from the following description and the accompanying drawings and will be pointed out in the annexed claims.

In the accompanying drawings, there has been disclosed a structure designed to carry out the various objects of the invention but it is to be understood that the invention is not confined to the exact features shown as various changes may be made within the scope of the claims which follow.

In the accompanying drawings forming 90 part of this specification,

Figure 1 is a sectional elevation of a form of envelope-making machine showing the invention applied thereto;

Figure 2 is a vertical sectional view showing in a general way, the operating mechanism mounted within the cylinder;

Figure 3 is a vertical sectional view on the line 3—3 of Figure 2;

Figure 4 is an enlarged detail sectional 100 view on the line 4—4 of Figure 2;

Figure 5 is an enlarged detail view showing the means provided at one end of the cylinder for actuating the movable blade of the cutting device;

Figure 6 is a plan view of the frame supporting the cutting device;

Figure 7 is a detail sectional view of the

spindle for supporting the roll of window material, showing the means provided within the cylinder for supporting the same;

5 Figure 8 is a view of the spindle removed from the cylinder;

Figure 9 is an enlarged detail sectional view on the line 9—9 of Figure 7;

10 Figure 10 is a detail sectional view on the line 10—10 of Figure 7;

Figure 11 is an enlarged detail sectional view on the line 11—11 of Figure 2, showing the means for adjusting the position of the friction wheel upon the hollow shaft;

15 Figure 12 is a cross sectional view on the line 12—12 of Figure 11;

Figure 13 is a plan view of a blank showing a window opening therein and a patch of transparent window material positioned thereover; and

20 Figure 14 is a view showing a completed envelope having a window therein.

In the selected embodiment of the invention here shown for purposes of disclosure, there is illustrated a portion of an envelope-making machine, comprising a main frame 15 having the usual pressure cylinder 16 and gumming cylinder 17 rotatably mounted thereon. The usual gumming device 18 is mounted on the frame 15 above the gumming cylinder 17. A conveyor 19 delivers the envelope blanks 21 to the pressure cylinder 16 and gumming cylinder 18, as shown in Figure 1.

An important feature of this invention resides in the novel means provided for applying the windows or patches of transparent material to the envelope blanks, after they have passed between the cylinders 16 and 17, and the surface thereof has been gummed 35 to receive the window patches. Such means consist of a hollow cylinder 22 rotatably mounted in bearings provided on the frame 15, and having a geared connection with the pressure cylinder 16, as shown in Figures 1 and 2. The cylinders 16 and 17 are similarly 40 geared together for simultaneous operation. As shown in Figures 1 and 2, the transparent material from which the windows are mounted in the form of a roll 23 within the hollow cylinder 22. A spindle 24 is mounted in the cylinder to provide a support for the material 23. This spindle, it will be noted by reference to Figures 7, 45 8, 9 and 10, is demountably supported within the cylinder 22. One end thereof is supported in a bearing 25, and the opposite end thereof is removably retained in a support 26 secured to one end of the cylinder by bolts as shown. This support 26 is open on 50 one side, as shown in Figures 9 and 10, and is provided with key ways 27, arranged to receive keys 28 terminally secured to the end of the spindle 24, as shown in Figures 7 and 10.

65 A set screw 29 is provided in the support

25 to secure the spindle thereto, when the machine is in operation. The construction of the support 26 is such that when the set screw 29 is loosened, the spindle 24 may be axially moved in the supports in a direction 70 toward the support 26 so as to move the keys 28 out of engagement, or out from under the lugs 31, after which the spindle may readily be removed from the supports 25 and 26, as indicated in dotted lines in Figure 7.

75 Roll 23 of transparent material is adjustably positioned upon the spindle 24 by the discs 32 and 33. The disc 32 has an integral sleeve 34 thereon, having its outer end slidably received in a bore 35, provided in a split clamping member 36, adjustably secured to the spindle by means of a clamp nut 37, received in threaded engagement therewith. The disc 33 is provided with an exteriorly threaded extension 38 having a lock nut 39 80 mounted thereon for securing the disc 33 in adjusted positions. The extension 38 is split, as shown in Figure 8, and is also slightly tapered so that when the nut 39 is rotated in a direction toward the disc, the extension 38 will securely clamp the disc to the spindle 24. A compression spring 41 is coiled about the sleeve 34 of the disc 32, and terminally engages the disc 32 and the clamping member 36. Thus by means of the above mechanism, the roll 23 of window material may be longitudinally adjusted upon the spindle 24 to properly align it with the window openings in the envelope blanks. In operation the discs 32 and 33 are engaged 100 with opposite sides of the roll 23 as shown in Figure 2, the adjustment of the discs being such as to put the compression spring 41 under a slight tension, sufficient to frictionally prevent the roll 23 from over-running during the operation of the machine. The roll, however, is rotatable upon the spindle, such rotation being governed by the feeding of the window material from the interior of the cylinder 22. The spindle 24 is non-rotatable with respect to the cylinder. A door or cover 42 is provided in the periphery of the cylinder 22 by means of which access may be had to the interior of the cylinder for the purpose of removing the spindle 24, when it is necessary to mount a new roll of window material thereon.

105 The means provided for feeding the sheet window material from the interior of the cylinder consists of a pair of feeding rolls 43 and 44 suitably geared together for simultaneous operation by means of gears 45 and 46, shown in dotted lines in Figure 4 and full lines in Figure 2. The feed roll 43 is rotatably mounted in suitable bell-cranks 47, pivotally mounted within the cylinder, as shown in Figures 1 and 4. Tension springs 48 connect one end of each bell-crank with the cylinder wall in such a manner as to cause the feed roll 43 to be yieldably held 115 120 125 130

in contact with the periphery of the feed roll 44 to feed the webbing therebetween. (See Figure 4.) The cylinder 22 preferably comprises two sections, the main section, 5 in which the roll 23 of window material is mounted, and adjacent the periphery of which is mounted the feeding and cutting mechanism for the window material. The comparatively smaller section 49 of the cylinder 10 provides a housing for the driving mechanism for the feed rolls 43 and 44, clearly shown in Figure 2.

The relatively smaller section 49 provides a housing for the driving mechanism for 15 the feed rolls 43 and 44, as shown in Figure 2. The abutting ends of the two cylinder sections are provided with annular flanges adapted to receive bolts for securing together the two sections. The feed roll 44 has 20 a reduced end portion 51 mounted in a bearing bracket 52 suitably secured to the flange of the cylinder section 49. A beveled gear 53 is terminally secured to the reduced end portion 51 and meshes with a beveled pinion 25 54 terminally mounted upon an upright hollow shaft 55 rotatably mounted in bearings 56 and 57 for movement with the cylinder. (See Figure 2.) The bearing 56 may be integrally formed with the bearing 30 bracket 52, while the bearing 57 is preferably bolted to a bracket 58 secured to the annular flange of the cylinder section 49. This bracket 58 is preferably integrally formed with the support 25, supporting one 35 end of the spindle 24.

A friction wheel 59 is slidably mounted upon the hollow shaft 55 and frictionally 40 45 engages a driving disk 61, slidably mounted upon a sleeve 62 secured to the main frame 15. The disk 61 is locked against rotation by means of a key 63 mounted in the sleeve 62. A threaded cap 64 is terminally secured to an adjusting rod 65, mounted in a bore in the sleeve 62. This cap 64 is in threaded 50 55 engagement with a threaded extension 66 provided on the disk 61. Referring to Figure 2, it will be noted that the inner face of the cap 64 engages the adjacent end of the sleeve 62. This cap is also fixedly secured to the rod 65 by means of a nut 67 as shown. The opposite end of the rod 65 is threaded to receive a locknut 68. When this nut is loosened, the rod 65 may be relatively rotated within the sleeve 62 by means of its 60 65 squared end 69. Such rotation of the rod 65 will move the disk 61 to or from the friction wheel 59 to increase or decrease the frictional contact between wheel and disk.

The friction wheel 59 is slidably mounted 60 65 upon the shaft 55 to provide for varying the feeding of the window material from the interior of the cylinder. The means provided for thus adjusting the position of the wheel 59 upon the shaft 55 is clearly shown 65 in Figure 11, and comprises a threaded stem

71 axially mounted within the shaft 55 and having a threaded engagement with a block 72, secured to the hub 73 of the friction wheel 59. The block 72 has a lug 74 engaged in a slot 75 terminally provided in the hub 73, as shown. A cap screw 76 secures the block to the hub 73. The shaft 55 is provided with a longitudinal slot 77 in which a portion of the threaded block 72 slides, when the friction wheel 59 is adjusted upon the shaft (see Figure 12). This slot 77 also prevents the friction wheel from relatively rotating upon the shaft 55. A threaded cap 78 is terminally mounted upon the shaft 55 and is secured thereto by means of 80 a setscrew 79. The threaded stem 71 is provided with an annular head or flange 81 adapted to engage the end of the hollow shaft 55 and also the adjacent inner face of the cap 78, as shown in Figure 11. This 85 flange prevents the stem 71 from longitudinally moving with respect to the shaft 55. The projecting end 82 of the stem 71 is squared to receive a socket wrench 83, as shown in dotted lines in Figure 2. An aperture 84 is provided in the wall of the cylinder section 49 through which the wrench 83 may be inserted to engage the stem 71. A spring-actuated cover plate 85 normally 90 closes the aperture 84. By means of the 95 above described mechanism, the relative position of the friction wheel 59 upon the hollow shaft 55 may readily be adjusted from the exterior of the cylinder, to vary the feeding of the material from the cylinder to correspond to the width of the window opening 100 in the envelope blank.

The means provided for severing the web of window material after a predetermined length thereof has been fed from the cylinder, consists of a movable knife blade 86 secured to a shaft 87, mounted in bearings provided in a frame 88, demountably secured to the peripheral wall of the cylinder as shown in Figure 4. A stationary blade 89 110 is secured to the frame 88 between which and the movable blade, the web of material is fed as shown in Figure 4. An elongated opening or slot 91 is provided in the frame 88 through which the web of window material is fed from the interior of the cylinder by means of the feed rolls 43 and 44. The shaft 87 projects from one end of the frame 88 and has an arm 92 terminally secured thereto, having a roller 93 mounted thereon 115 adapted to engage a stationary cam 94, adjustably secured to the main frame 15, as shown in dotted lines in Figure 2. When the cylinder is rotated, the roller 93 will engage the cam 94, as indicated in dotted lines in 120 Figure 5, thereby oscillating it from the full to the dotted line position, shown in this figure, with the resultant actuation of the movable knife or blade 86, thereby severing the web. The arm 92 is provided with a lug 130

95 which is engaged by one end of a compression spring 96, the other end of which is seated against a stationary lug 97 provided upon the end wall of the cylinder. An 5 adjusting screw 98 is mounted in a similar lug 99 and engages the lug 95 of the arm 92 to provide a limit stop therefor, and also to provide means for adjusting the position 10 of the knife blade 86 with respect to the stationary blade 89. A spring-actuated bar 101 is movably mounted in the frame 88 and normally is retained in the position shown in Figure 4. When the movable blade 86 is actuated to sever the web, the bar 101 will 15 be depressed against the tension of the spring 102. As soon as the blade 86 returns to its normal position, the bar 101 will return to its normal position, thereby guiding the web of material over the edge of the stationary blade 89 and through the elongated opening 91, through which it is fed from the interior of the cylinder. The construction and arrangement of the knife-holding frame 88 is such that it may readily be removed 20 from the cylinder, when desired, to allow for adjusting the blades 86 and 89 and for sharpening them when it becomes necessary.

In the operation of this novel mechanism 30 for applying windows to envelope blanks, the blanks are fed between the pressure cylinder or roll 16 and the hollow cylinder 22. During the rotation of the cylinder 22, the window material will be fed from the interior of the cylinder through the elongated opening in the knife frame 88, at a speed corresponding to the length of patch required for covering the size of the window opening in the blank, as shown in Figure 13. 35 As soon as the end of the window material, projecting from the interior of the cylinder, engages the envelope blank, the movable blade 86 will be actuated to sever the web, after which it will be pressed into contact 40 with the adjacent face of the blank and secured thereto as a result of the surface of the blank previously having been gummed by the gumming cylinder 17. After the patch of window material has thus been applied 45 to the blank, the latter may be discharged onto a suitable receiving means such as the flysticks 103, and subsequently deposited onto a table 104, as shown in Figure 1. The cylinder 22 and its operating mechanism 50 is so constructed that the feeding of the material from the cylinder may be varied to suit practically all standard sizes of window openings. The roll of window material may also be longitudinally adjusted upon the 55 spindle 24 to properly align it with the window openings in the blanks. The length of the cylinder 22 is sufficient to allow for maximum widths of window material, as 60 will readily be seen by reference to Figure 2. 65 Thus, the above described mechanism is ap-

plicable for practically all sizes of envelope window openings. It will also be noted by reference to Figures 1 and 2, that the window-applying mechanism is all contained within the cylinder 22, thereby providing 70 such a device which may be used as an attachment for envelope-making machines of ordinary construction, thereby adapting such machines for use in applying the windows to the window openings in the blanks 75 in the same operation as the envelopes are made, thereby greatly reducing the cost of manufacturing envelopes having windows in the faces thereof.

I claim as my invention:

1. The combination with a cylinder mounted for rotation and having an elongated opening in its periphery, of a roll of sheet material mounted in the cylinder, means for feeding the material from the cylinder 85 through said elongated opening, simultaneously as the cylinder is rotated, means for varying the feed of the material, and a cutting means for severing said sheet upon a predetermined rotation of the cylinder. 90

2. A machine of the class described, including in combination, a pair of rolls for feeding envelope blanks having window openings therein, a device for gumming the surface of each blank around the window 95 opening thereof, a cylinder mounted adjacent one of said rolls and cooperating therewith to receive the gummed envelopes therebetween, a supply of transparent sheet material stored in the cylinder, an adjustable feeding 100 mechanism for feeding predetermined length of said material from the cylinder simultaneously as the latter is rotated, and a cutting device for severing said sheet whereby the severed portion may be transferred onto the 105 gummed surface of the blank to provide a window for the opening therein.

3. A machine of the class described, including in combination, a pair of rolls for feeding envelope blanks having window 110 openings therein, a device for gumming the surface of each blank around the window opening thereof, a cylinder mounted adjacent one of said rolls and between which roll and cylinder the blanks are successively 115 fed, a supply of transparent sheet material stored in the cylinder, a variable speed feeding mechanism in the cylinder for feeding the material from the cylinder simultaneously as it is rotated, a cutting device for transversely severing the sheet adjacent the cylinder periphery whereby the severed portion may be transferred onto the gummed surface of the blank to provide a window 120 for the opening therein, and means exteriorly of the cylinder for actuating said cutting device.

4. A machine of the class described, including a pair of rolls between which envelope blanks are fed, a device for gumming 125

- the surface of each blank around the window opening thereof, a cylinder mounted adjacent one of said rolls and having a driving connection therewith, said roll and cylinder being arranged to receive the gummed blanks therebetween, a roll of transparent sheet window material rotatably mounted within the cylinder, feed rolls in the cylinder for gradually feeding the material therefrom through an opening in the wall of the cylinder, a cutting device in the cylinder for transversely severing the material, whereby the severed portion thereof will be transferred onto and secured to a blank to provide a window for the opening thereof, when the latter is passed between the cylinder and its complementary roll, and a variable speed driving mechanism in the cylinder for operating said feed rolls.
5. A machine of the class described, including in combination, a means for feeding envelope blanks having window openings therein, a device for gumming the surface of each blank around the window opening thereof, a hollow cylinder, a complementary roll mounted adjacent the cylinder and having a geared connection therewith, said cylinder and roll being arranged to receive and feed the gummed blanks therebetween, a roll of transparent sheet window material rotatably mounted within the cylinder, feed rolls in the cylinder adapted to continuously feed the material therefrom through an opening in the wall of the cylinder, when the latter is rotated, a cutting device in the cylinder for transversely severing the material at the periphery of the cylinder when the material fed from the cylinder engages the complementary roll, whereby the severed portion thereof may be transferred onto and secured to a gummed blank to provide a window for the opening therein, when the latter is passed between the cylinder and said roll, and an operating mechanism in the cylinder for varying the feeding of the material from the cylinder.
6. A machine of the class described, including a mechanism for feeding and gumming envelope blanks having window openings therein, a cylinder mounted for rotation adjacent said feeding mechanism, a spindle removably mounted within said cylinder and adapted to support a roll of transparent sheet window material, a pair of feed rolls mounted in the cylinder and adapted to feed the material from the interior of the cylinder through an opening in the wall thereof, a cutting device mounted adjacent the periphery of the cylinder, said device including a stationary blade and a movable blade mounted in a frame demountably secured to the wall of the cylinder and forming a portion of the periphery thereof, and means at one end of the frame for operating said movable blade.
7. A machine of the class described, including a rotatably mounted cylinder, a spindle mounted within said cylinder and adapted to support a roll of sheet material, a pair of feed rolls mounted in the cylinder and adapted to feed the material from the interior of the cylinder through an opening in the wall thereof, a cutting device for the material, mounted adjacent the periphery of the cylinder and operable from the exterior of the cylinder to sever the material upon a predetermined rotation of the cylinder, and a friction drive for the feed rolls mounted within the cylinder and operable, upon rotation of the cylinder, to rotate the feed rolls to feed the material from the cylinder, said drive including a disk having a wheel frictionally engaged therewith and adjustable to vary the feed of the material from the cylinder.
8. A machine of the class described, including a cylinder mounted for rotation and having an elongated opening in the wall thereof, a spindle removably mounted within the cylinder and adapted to support a roll of sheet window material, feed rolls in the cylinder for feeding the material therefrom, a cutting device also in the cylinder for severing the material after a predetermined length has been fed through the opening in the wall of the cylinder, a shaft diametrically mounted in said cylinder and having a geared connection with one of said feed rolls, and a friction wheel slidably mounted upon said shaft and engagable with a stationary disc for transmitting rotary movement to said feed rolls when said cylinder is rotated.
9. A machine of the class described, including a cylinder mounted for rotation and having an elongated opening in the wall thereof, a spindle removably mounted within the cylinder and adapted to support a roll of sheet material, a mechanism in the cylinder for feeding the material therefrom, a cutting device also in the cylinder for severing the material after a predetermined length has been fed through the opening in the wall of the cylinder, a hollow shaft diametrically mounted in said cylinder and having a geared connection with said feeding mechanism, a friction wheel slidably mounted upon said shaft and engagable with a stationary disc for transmitting rotary movement to said mechanism when the cylinder is rotated, and means mounted in said hollow shaft for adjusting the position of said friction wheel upon said shaft to vary the feeding of the material from the cylinder.
10. A machine of the class described, including a rotatably mounted cylinder, means therein for receiving and supporting a roll of sheet material, geared-together rolls for feeding the material from the cylinder when

the latter is rotated, a friction drive for operating said feed rolls, said drive including a friction wheel rotatably mounted for movement with the cylinder, and a stationary disc also mounted in the cylinder and frictionally engaging said wheel.

11. A machine of the class described, including a hollow cylinder, means therein for receiving and supporting a roll of sheet material, rolls for feeding the material from the cylinder when the latter is rotated, a friction drive for operating said feed rolls, said drive including a friction wheel rotatably mounted for movement with the cylinder, a stationary disc also mounted in the cylinder and frictionally engaging said wheel.

12. A machine of the class described, including a cylinder having means therein for receiving and supporting a roll of sheet material, rolls for feeding the material from the cylinder when the latter is rotated, a friction drive for operating said feed rolls including a friction wheel adapted to frictionally engage a stationary disc also mounted in the cylinder, a stationary sleeve for slidably supporting said disc, means for preventing relative rotation of the disc upon the sleeve, and a rod axially mounted in said sleeve and having a threaded connection with the disc whereby, when the rod is relatively rotated, the disc will be axially moved to increase or decrease the frictional contact between wheel and disc.

13. A machine of the class described, including a hollow cylinder comprising two sections secured together, one section having means therein for receiving and supporting a roll of sheet material, a mechanism for feeding the material from the cylinder through an opening in the periphery thereof, and a device for transversely severing the material at the periphery of the cylinder, upon a predetermined rotation thereof, and the other section having a driving mechanism therein for continuously operating said material feeding mechanism, when the cylinder is rotated.

14. A machine of the class described, in-

cluding a hollow cylinder comprising two sections secured together for operation as a unit, one section having means therein for receiving and supporting a roll of sheet material, a mechanism for feeding the material from the cylinder through an opening in the periphery thereof, and a device for transversely severing the material at the periphery of the cylinder, upon a predetermined rotation thereof, the other section having a driving mechanism therein for continuously operating said material feeding mechanism, when the cylinder is rotated, said driving mechanism comprising a shaft diametrically mounted in said section and having a geared connection with said feeding mechanism, and a friction wheel mounted upon said shaft and engageable with a stationary disc mounted within said section.

15. The combination with a driven cylinder having an aperture in the peripheral wall thereof, of a spindle axially mounted therein and adapted to support a roll of sheet material, feed rolls adjacent the aperture for feeding the material from the cylinder through said aperture, a drive shaft diametrically mounted in the cylinder and having a geared connection with the feed rolls, and a friction drive within the cylinder for operating the drive shaft.

16. The combination with a cylinder mounted for rotation and having an elongated opening in its periphery, extending lengthwise of the cylinder, of a roll of sheet material mounted in the cylinder and adapted for relative rotation therein, power-operated feed rolls in the cylinder for feeding the sheet of material therefrom through said opening, when the cylinder is rotated, a friction drive for the feed rolls, comprising a disk and a wheel frictionally engaged therewith and adjustable to vary the feed of the material, and a cutting means mounted in the cylinder and adapted to sever the sheet adjacent the cylinder periphery, upon a predetermined rotation of said cylinder.

In witness whereof, I have hereunto set my hand this 18th day of October, 1926.

CHARLES E. DAMMART.
